(57) **ABSTRACT**

An image forming apparatus includes first and second heaters and a controller. The first and second heaters have a same light distribution and heat a roller of an image fixing unit. The second heater generates a less heat amount than the first heater. The controller applies a drive voltage to a heater of the heaters. When a heat amount generated by the second heater has increased to a first threshold value by the controller controlling the drive voltage, the controller switches the drive-voltage-applied heater from the second heater to the first heater. When a heat amount generated by the first heater has decreased to a second threshold value smaller than the first threshold value by the controller controlling the drive voltage, the controller switches the drive-voltage-applied heater from the first heater to the second heater.

DUTY CYCLED HALOGEN LAMP IMAGE FORMING APPARATUS

CROSS-REFERENCE TO RELATED APPLICATIONS

This application claims priority under the Paris Convention to Japanese Patent Application No. 2016-018558 filed on Feb. 3, 2016, the entire disclosure of which is incorporated herein by reference.

BACKGROUND OF THE INVENTION

1. Field of the Invention

The present invention relates to an image forming apparatus.

2. Description of the Related Art

In fixing control of an image forming apparatus, typically, a halogen lamp heater is used as a fixing heater, and temperature of the fixing heater is controlled by ON/OFF control. In order to control the temperature more finely, there is a control method of supplying drive voltage of appropriately selected half-waves of AC waveform to a halogen lamp heater.

In this kind of control method, the number of half-waves of the AC waveform in a predetermined period (duty cycle) is appropriately selected according to the heat amount to be required, and the effective value of drive voltage to be supplied to a halogen lamp heater changes according to the selected number of half-waves of the AC waveform.

Meanwhile, for a halogen lamp heater, there is a reference voltage with which halogen cycle occurs most efficiently. If the number of selected half-waves (i.e., the selected number of half-waves) of the AC waveform is small, and hence the effective value of drive voltage to be supplied to a halogen lamp heater is smaller than the reference voltage, the temperature of a filament (tungsten) of the halogen lamp heater becomes low, and a phenomenon that the filament is eaten away, called "chemical attack", occurs.

Then, there is a heater control device (Japanese Patent Application Publication No. 2011-257604) which, in order to let halogen cycle occur in the standby mode too, fully turns on (ON) a halogen lamp heater at predetermined time intervals, and when a filament thereof reaches a predetermined temperature, supplies drive voltage of appropriately selected half-waves of the AC waveform to the halogen lamp heater without turning off (OFF) the halogen lamp heater, thereby reducing flicker as well as preventing breaking of the filament.

The heat amount required for image forming depends on the type and/or the thickness of paper, which is a recording medium. For example, in the case of image forming on thin paper, the required heat amount is small, and therefore the application pattern for drive voltage has a small number of half-waves of the AC waveform selected in a predetermined period (low duty cycle). In this case, the duty cycle of the application pattern is limited to a predetermined value or more, which can prevent chemical attack and extend life of the halogen lamp heater.

However, even if, in order to prevent chemical attack, the duty cycle of the application pattern is limited to the predetermined value or more in the case of image forming on thin paper, the heater cannot be kept ON if the heat amount generated by turning on the heater with the application pattern having the duty cycle is more than the required heat amount, and needs to be turned off at appropriate timing to make the heat amount close to the required

heat amount. Such temperature control cannot stabilize the temperature of a fixing roller.

Then, a plurality of heaters of the same light distribution, the sum of the heat amounts of the heaters being the maximum heat amount required for "fixing" (i.e., fixing the toners to the paper), is provided, and the heaters are used in combination, and turned on with the application pattern having the duty cycle of the predetermined value required to prevent chemical attack or more, thereby being controlled to continuously generate a predetermined heat amount. Further, the heaters include at least one heater which generates a heat amount being the minimum heat amount required for fixing or less when turned on with the application pattern having the duty cycle of the predetermined value. This can stabilize the temperature of a fixing roller.

However, in order to continuously generate a predetermined heat amount by combination of the heaters, it is necessary to change the lighting with the heaters at appropriate timing. If the heat amount required for fixing is a heat amount near the borderline where switching from one heater to another is performed, frequent switching between these two heaters may occur, which causes flicker.

BRIEF SUMMARY OF THE INVENTION

One or more embodiments of the present invention provide an image forming apparatus that can prevent flicker.

According to one or more embodiments of the present invention, an image forming apparatus includes: a first halogen lamp heater and a second halogen lamp heater which have a same light distribution and heat a fixing member of an image fixing unit, the second halogen lamp heater generating a less heat amount than the first halogen lamp heater; an AC power supply; a temperature sensor which detects a temperature of the fixing member; and a controller which determines a combination of the first and second halogen lamp heaters based on output of the temperature sensor, and applies a drive voltage of a half-wave of an AC waveform of the AC power supply to a halogen lamp heater of the first and second halogen lamp heaters, the half-wave being selected based on an application pattern having a duty cycle of a predetermined value or more, wherein the second halogen lamp heater generates a heat amount being a minimum heat amount required for fixing or less when turned on with the application pattern having the duty cycle of the predetermined value, when a heat amount generated by the second halogen lamp heater has increased to a first threshold value by the controller controlling the drive voltage to apply, the controller switches the halogen lamp heater, to which the drive voltage is applied, from the second halogen lamp heater to the first halogen lamp heater, and when a heat amount generated by the first halogen lamp heater has decreased to a second threshold value which is smaller than the first threshold value by the controller controlling the drive voltage to apply, the controller switches the halogen lamp heater, to which the drive voltage is applied, from the first halogen lamp heater to the second halogen lamp heater.

In one or more embodiments, the image forming apparatus further includes a table in which the combination (or combined heat amount) of the first and second halogen lamp heaters and the duty cycle of the predetermined value or more are set forth, wherein the controller calculates a required heat amount based on the output of the temperature sensor, and selects the combination of the first and second halogen lamp heaters and the duty cycle which satisfy the required heat amount.

In one or more embodiments, in the image forming apparatus, the first threshold value is a maximum heat amount generated by the second halogen lamp heater, and the second threshold value is a heat amount generated by the first halogen lamp heater turned on with the application pattern having the duty cycle of the predetermined value.

In one or more embodiments, in the image forming apparatus, the controller fully turns on the first halogen lamp heater and applies the drive voltage to the second halogen lamp heater when a heat amount required for fixing is more than a maximum heat amount generated by the first halogen lamp heater.

In one or more embodiments, in the image forming apparatus, a heat amount generated by any of the first and second halogen lamp heaters turned on with the application pattern having the duty cycle of the predetermined value is a heat amount required to prevent breaking of a filament of any of the first and second halogen lamp heaters.

BRIEF DESCRIPTION OF THE SEVERAL VIEWS OF THE DRAWING

The present invention is fully understood from the detailed description given hereinafter and the accompanying drawings, which are given by way of illustration only and thus are not intended to limit the present invention, wherein:

FIG. 1 shows the schematic configuration of an image forming apparatus according to one or more embodiments of the present invention;

FIG. 2 is a block diagram showing the main functional components of the image forming apparatus;

FIG. 3 is a schematic view showing the configuration of an image fixing unit according to one or more embodiments of the present invention;

FIG. 4 is a schematic view showing the internal configuration of a fixing roller according to one or more embodiments of the present invention;

FIG. 5 is a control circuit diagram of the image fixing unit;

FIG. 6 is an explanatory view showing an example of selecting operation of half-waves of AC waveform;

FIG. 7 is a flowchart showing an example of operation of the image forming apparatus; and

FIG. 8 shows a table as an example in accordance with one or more embodiments of the present invention.

DETAILED DESCRIPTION OF EMBODIMENTS

[1. Explanation of Configuration According to One or More Embodiments of the Present Invention]

Hereinafter, an image forming apparatus according to one or more embodiments of the present invention is described with reference to the drawings.

FIG. 1 shows the schematic configuration of an image forming apparatus 1, according to one or more embodiments of the present invention. FIG. 2 is a block diagram showing the main functional components of the image forming apparatus 1.

The image forming apparatus 1 includes: a controller 10 having a CPU 101 (Central Processing Unit), a RAM 102 (Random Access Memory) and a ROM 103 (Read Only Memory); a storage unit 11; an operation unit 12; a display unit 13; an interface 14; a scanner 15; an image processing unit 16; an image forming unit 17; an image fixing unit 18; and a conveying unit 19. The controller 10 is connected to the storage unit 11, the operation unit 12, the display unit 13, the interface 14, the scanner 15, the image processing unit

16, the image forming unit 17, the image fixing unit 18 and the conveying unit 19 via a bus 21.

The CPU 101 reads and executes various control programs stored in the ROM 103 or the storage unit 11, thereby performing various types of arithmetic processing.

The RAM 102 offers a working memory space to the CPU 101 and temporarily stores data.

The ROM 103 stores the various control programs, which are executed by the CPU 101, setting data and so forth. Instead of the ROM 103, a rewritable nonvolatile memory, such as an EEPROM (Electrically Erasable Programmable Read Only Memory) or a flash memory, may be used.

The controller 10, which has the CPU 101, the RAM 102 and the ROM 103, controls all the units or the like of the image forming apparatus 1 in accordance with the above various control programs. For example, the controller 10 causes the image processing unit 16 to perform predetermined image processing on image data and the storage unit 11 to store the processed image data. Further, the controller 10 causes the conveying unit 19 to convey paper and the image forming unit 17 to form images on the paper based on the image data stored in the storage unit 11.

The storage unit 11 is constituted of a DRAM (Dynamic Random Access Memory), which is a semiconductor memory, and/or an HDD (Hard Disk Drive), and stores image data obtained by the scanner 15, image data input from the outside via the interface 14, and so forth. These image data and so forth may be stored in the RAM 102.

The operation unit 12 includes an input device, such as operation keys and/or a touch panel disposed on the screen of the display unit 13, and converts input operations to the input device into operation signals, and outputs the operation signals to the controller 10.

The display unit 13 includes a display device, such as an LCD (Liquid Crystal Display), and displays status of the image forming apparatus 1, operation screens showing contents of the input operations to the touch panel, and so forth.

The interface 14 sends/receives data to/from external computers, other image forming apparatuses and so forth, and constituted of any one of various serial interfaces.

The scanner 15 reads images formed on paper, generates image data containing single-color image data of color components of R (red), G (green) and B (blue), and stores the generated image data in the storage unit 11.

The image processing unit 16 includes a rasterization unit, a color conversion unit, a gradation correction unit and a half toning unit, and performs various types of image processing on the image data stored in the storage unit 11, and stores the processed image data in the storage unit 11.

The image forming unit 17 forms images on paper based on the image data stored in the storage unit 11. The image forming unit 17 includes four image forming sections for respective color components of C (cyan), M (magenta), Y (yellow) and K (black). Each image forming section includes an exposure unit 171, a photoreceptor 172 and a development unit 173. The image forming unit 17 also includes a transfer body 174 and a pair of secondary transfer rollers 175.

The exposure unit 171 includes an LD (Laser Diode) as a light emitting element. The exposure unit 171 drives the LD on the basis of image data, and irradiates and exposes the charged photoreceptor 172 with and to laser light, thereby forming an electrostatic latent image on the photoreceptor 172. The development unit 173 supplies a toner (color material) of a predetermined color (C, M, Y or K) onto the

exposed photoreceptor 172 with a charged roller, thereby developing the electrostatic latent image formed on the photoreceptor 172.

The images respectively composed of the C, M, Y and K toners (single-color images) on the four photoreceptors 172 respectively for C, M, Y and K are successively transferred from the respective photoreceptors 172 to the transfer body 174 to be superposed on top of one another, thereby forming a multi-color image composed of C, M, Y and K color components on the transfer body 174. The transfer body 174 is an endless belt wound around transfer-body conveying rollers and rotates as the transfer-body conveying rollers rotate.

The pair of secondary transfer rollers 175 transfers the multi-color image on the transfer body 174 to paper fed from a paper feed tray 22 or an external paper feeding device. To be specific, a predetermined transfer voltage is applied to the secondary transfer rollers 175 sandwiching the paper and the transfer body 174, which attracts the toners of the multi-color image on the transfer body 174 to the paper side and thus transfers the multi-color image to the paper.

The image fixing unit 18 heats and presses the paper, to which the toners have been transferred, thereby fixing the toners to the paper, namely, performing fixing.

FIG. 3 is a schematic view showing the configuration of the image fixing unit 18. The image fixing unit 18 includes a fixing roller 183, a pressure roller 184 and a temperature sensor 185. The image forming unit 18 and the controller 10 constitute a fixing device.

The fixing roller 183 includes halogen lamp heaters 186 and 187 each of which is a fixing lamp (or fixing heater) extending in the rotation axis direction. The halogen lamp heaters 186 and 187 generate heat by being electrified under the control of the controller 10. The fixing roller 183 rotates by being driven by a not-shown rotary drive unit, such as a motor, under the control of the controller 10. The fixing roller 183 is provided with the temperature sensor 185 which detects temperature of the fixing roller 183. As long as the temperature of the fixing roller 183 can be detected, the number of temperature sensors 185 to be provided is not limited to one and may be two or more.

FIG. 4 is a schematic view showing the internal configuration of the fixing roller 183.

The halogen lamp heaters 186 and 187 are respectively constituted of tungsten filaments 186b and 187b in their respective cylindrical parts 186a and 187a. Each of the cylindrical parts 186a and 187a is filled with a halogen gas of a predetermined concentration. Based on the concentration of the halogen gas with which each of the cylindrical parts 186a and 187a is filled, the reference voltage is set for each of the halogen lamp heaters 186 and 187.

The halogen lamp heaters 186 and 187 are halogen lamp heaters of the same light distribution, and the filaments 186b and 187b are configured to heat the middle portion in the axis direction of the fixing roller 183 (middle-portion light distribution).

As a matter of course, the fixing roller 183 may have, in addition to the halogen lamp heaters 186 and 187, a halogen lamp heater(s) of whole-area light distribution, which heats the whole area in the axis direction of the fixing roller 183, and/or a halogen lamp heater(s) of end-portion light distribution, which heats the end portions in the axis direction of the fixing roller 183.

As shown in FIG. 3, the pressure roller 184 is biased in a direction to approach the fixing roller 183 by an elastic member (not shown), thereby contacting the fixing roller

183 by pressure, and rotates as the fixing roller 183 rotates while forming a fixing nip with the fixing roller 183.

The pressure roller 184 may rotate by being driven by a not-shown rotary drive unit, such as a motor, under the control of the controller 10.

The fixing roller 183 and the pressure roller 184 heat and press paper P as a recording medium while sandwiching the paper P at the fixing nip and conveying the paper P in a conveying direction R indicated by an arrow in FIG. 3. Thus, 10 the fixing roller 183 and the pressure roller 184 melt and fix toners on the paper P. Temperature of the fixing roller 183 when the fixing roller 183 contacts the paper P should be, for example, within a range from 180° C. to 200° C. inclusive. Hence, the halogen lamp heaters 186 and 187 heat the fixing 15 roller 183 such that the temperature of the fixing roller 183 becomes within the range.

As shown in FIG. 1, the conveying unit 19 includes pairs of paper-conveying rollers which convey paper by rotating in the state of sandwiching the paper, and conveys paper 20 along a predetermined conveying path. The conveying unit 19 also includes a reversing mechanism 191 which reverses paper having been subjected to fixing of the image fixing 25 unit 18 and conveys the paper to the secondary transfer rollers 175. In the image forming apparatus 1, in the case of double-side image-forming, paper is ejected to a paper receiving tray 23 after being reversed by the reversing mechanism 191, thereby having images on both sides of the paper, whereas in the case of single-side image-forming, paper is ejected to the paper receiving tray 23 without being 30 reversed by the reversing mechanism 191, thereby having an image(s) on one side of the paper.

[2. Explanation of Control Circuit of Image Fixing Unit According to One or More Embodiments of the Present Invention]

An AC power supply 1811 in FIG. 5 outputs normal AC voltage (e.g., 100 V or 200 V and 50 Hz or 60 Hz).

Each of switching elements 1812 and 1813 is a thyristor, a bidirectional thyristor (TRIAC) or the like, and becomes “ON” and conducts electricity when a trigger signal is 40 applied to the gate as a control terminal. Output of the AC power supply 1811 is connected to input terminals of the switching elements 1812 and 1813, and output terminals of the switching elements 1812 and 1813 are respectively connected to the input terminals of the halogen lamp heaters 186 and 187.

The controller 10 performs temperature control on the halogen lamp heaters 186 and 187. More specifically, the controller 10 functions as a power controller together with the switching elements 1812 and 1813, and controls the switching elements 1812 and 1813 with control signals (CS181 and CS182) and supplies, to the halogen lamp heaters 186 and 187, drive voltage of selected half-waves of the AC waveform output from the AC power supply 1811.

The temperature sensor 185 can be any type of temperature detection element, and is disposed near the fixing roller 183. The temperature sensor 185 detects and outputs the temperature of the fixing roller 183 to the controller 10.

A zero-crossing detection unit 1814 takes in the output of the AC power supply 1811, and generates and outputs a zero-crossing signal ZC181 to the controller 10.

[3. Explanation of Selection of Half-Waves of AC Waveform]

Herein, with reference to FIG. 6, described is a method of supplying, to the halogen lamp heaters 186 and 187, drive voltage of selected half-waves of the AC waveform output from the AC power supply 1811 using the switching elements 1812 and 1813.

As shown in B portion of FIG. 6, the zero-crossing detection unit **1814** detects each point at which the AC waveform output from the AC power supply **1811** passes through ± 0 V, and generates and outputs to the controller **10** the zero-crossing signal **ZC181** of an output value which is changed (from/to positive to/from negative) when the point is detected.

As shown in C portion of FIG. 6, the controller **10** generates and applies the control signal **CS181** (or control signal **CS182**) synchronized with the input zero-crossing signal **ZC181** to the control terminal of the switching element **1812** (or switching element **1813**).

That is, as shown in FIG. 6, in each of times **T1**, **T2** and **T4** in which the control signal **CS181** (or control signal **CS182**) is applied from the controller **10** to the switching element **1812** (or switching element **1813**), the switching element **1812** (or switching element **1813**) becomes “ON” and conducts electricity (conduction state), so that in each of the times **T1**, **T2** and **T4**, the half-wave of the AC waveform output from the AC power supply **1811** is selected (picked) and supplied to the halogen lamp heater **186** (or halogen lamp heater **187**).

On the other hand, in a time **T3** in which the control signal **CS181** (or control signal **CS182**) is not applied from the controller **10** to the switching element **1812** (or switching element **1813**), the switching element **1812** (or switching element **1813**) stays “OFF” and keeps not conducting electricity (non-conduction state), so that in the time **T3**, the half-wave of the AC waveform output from the AC power supply **1811** is not selected.

The switching element **1812** (or switching element **1813**) keeps the conduction state once the trigger signal (control signal) is applied to the gate thereof, but returns to the non-conduction state when, as the AC waveform, the voltage becomes 0 V. Hence, even when the switching element **1812** (or switching element **1813**) takes the conduction state in the time **T2**, it automatically returns to the non-conduction state in the time **T3**.

[4. Explanation of Operation of Image Forming Apparatus]

Herein, operation of the image forming apparatus **1** is described, using a flowchart shown in FIG. 7.

In FIG. 7, it is assumed that the lower limit of the duty cycle of the application pattern to generate the heat amount required to prevent chemical attack on the halogen lamp heaters **186** and **187** (breaking of the filaments **186b** and **187b**) is 40% as an example.

Further, it is assumed that in the image forming apparatus **1**, the maximum heat amount required for fixing is 1800 W and the minimum heat amount required for fixing is 300 W (obtained by actual measurement or the like) as an example.

A halogen lamp heater of 750 W (750 W $\times$ 40% = 300 W) or less can handle the minimum heat amount required for fixing. Hence, the operation is described with two halogen lamp heaters **186** and **187** of the same light distribution (middle-portion light distribution) respectively having the maximum heat amounts of 700 W and 1100 W (the sum of the maximum heat amounts is 1800 W).

Similar, if not the same, operation to that shown in FIG. 7 can be performed as long as a plurality of halogen lamp heaters of the same light distribution is provided. Hence, the operation can also be performed with a plurality of halogen lamp heaters of the whole-area light distribution or a plurality of halogen lamp heaters of the end-portion light distribution.

The controller **10** starts fixing (Step **S701**), and obtains the temperature of a portion of the fixing roller **183**, the portion

corresponding to the light distribution (e.g., middle-portion light distribution) of the halogen lamp heaters **186** and **187** (Step **S702**).

Then, the controller **10** calculates a heat amount (called “total duty cycle” herein) to be output by the two halogen lamp heaters **186** and **187** (Step **S703**).

For calculation of the total duty cycle to be output by the two halogen lamp heaters **186** and **187**, the controller **10** calculates the total duty cycle with the following calculation formula, for example.

$$\text{Difference} = \text{Target Temperature} - \text{Current Temperature}$$

$$\text{Total Duty Cycle} = K_p \times \text{Difference} + K_i \times \text{Accumulation of Differences}$$

In the above formula, K_p and K_i are constants.

The controller **10** determines to which halogen lamp heater the drive voltage of half-waves of the AC waveform of the AC power supply is currently applied, the half-waves being selected based on the application pattern (hereinafter called “duty control”) (Step **S704**).

When determining that the currently duty-controlled halogen lamp heater is the 700 W halogen lamp heater **186**, and the 1100 W halogen lamp heater **187** is fully turned on (i.e., controlled with a duty cycle of 100%) (Step **S704**; 700 W + 1100 W (ON)), the controller **10** determines a combination of the halogen lamp heaters and so forth which satisfy the calculated total duty cycle, referring to a table (Step **S705**), and supplies drive voltage based on the determined combination of the halogen lamp heaters and so forth to the appropriate (determined) halogen lamp heater and thereby controls the same (Step **S706**).

The table which the controller **10** refers to at Step **S705** is a table in which the combination of the halogen lamp heaters **186** and **187** and the duty cycle of the application pattern are set forth. The table is stored in advance in the ROM **103** of the controller **10** or the storage unit **11**.

The “combination of the halogen lamp heaters” herein includes a combination of the two halogen lamp heaters **186** and **187** (i.e., both of them are used) and a selection of either one of the halogen lamp heaters **186** and **187** (i.e., one of them is used).

For example, as shown in FIG. 8, in the range of the required heat amount being small (from 280 W to 700 W), the 700 W halogen lamp heater **186** is used, and the duty cycle of the application pattern for drive voltage to be supplied thereto is controlled.

For example, as shown in FIG. 8, in the range of the required heat amount being large (from 513 W to 1100 W), the 1100 W halogen lamp heater **187** is used, and the duty cycle of the application pattern for drive voltage to be supplied thereto is controlled.

For example, as shown in FIG. 8, in the range exceeding the maximum heat amount of the halogen lamp heater **187** (from 1380 W to 1800 W), the 1100 W halogen lamp heater **187** is fully turned on (i.e., controlled with a duty cycle of 100%), and also the 700 W halogen lamp heater **186** is used, and the duty cycle of the application pattern for drive voltage to be supplied thereto is controlled.

Fully turning on the 1100 W halogen lamp heater **187**, which has a larger maximum heat amount, and performing duty control on the 700 W halogen lamp heater **186**, which has a smaller maximum heat amount, can reduce fluctuation in power to be supplied to the halogen lamp heaters and therefore can prevent flicker.

As shown in FIG. 8, 280 W (less than 300 W which is the minimum heat amount required for fixing) to 1800 W

(maximum heat amount) can be generated with predetermined resolutions. This can eliminate the need to turn off a halogen lamp heater (s) at appropriate timing to make the heat amount close to the required heat amount, and can stabilize the temperature of a fixing roller.

The application pattern for drive voltage to be supplied to the halogen lamp heaters **186** and **187** is an application pattern to appropriately select half-wave(s) of the AC waveform from among, for example, 15 half-waves as one period. The number of half-waves in one period in the application pattern, from which (a) half-waves can be selected, is not limited to 15 as a matter of course.

In the table shown in FIG. 8, the lowest duty cycle of the application pattern for drive voltage to be supplied to the halogen lamp heaters **186** and **187** is 40%. This can generate the heat amount required to prevent chemical attack (breaking of the filaments **186b** and **187b**).

However, total duty cycles in the range RG91 shown in FIG. 8 are covered by either of the halogen lamp heaters being duty-controlled. Hence, if the heat amount required for fixing is in the range RG91, frequent switching between the two halogen lamp heaters may occur, which causes flicker.

Then, timing to switch from the halogen lamp heater **186** to the halogen lamp heater **187** and timing to switch from the halogen lamp heater **187** to the halogen lamp heater **186** are controlled to be different, namely, to have, what is called, hysteresis, which can prevent frequent switching between the two halogen lamp heaters.

That is, when determining that the currently duty-controlled halogen lamp heater is the 700 W halogen lamp heater **186** (Step S704; 700 W), the controller **10** determines whether the total duty cycle has reached a first threshold value TH91 (Step S707).

The first threshold value TH91 is a threshold value to switch from the halogen lamp heater **186** to the halogen lamp heater **187**, and equivalent to a total duty cycle of 40.7% in the table shown in FIG. 8, for example.

When determining that the total duty cycle has not reached the first threshold value TH91 yet (Step S707; NO), the controller **10** proceeds to Step S705. On the other hand, when determining that the total duty cycle has reached the first threshold value TH91 (Step S707; YES), the controller **10** switches the halogen lamp heater to perform duty control thereon from the 700 W halogen lamp heater **186** to the 1100 W halogen lamp heater **187** and also determines the duty cycle of the halogen lamp heater **187** which satisfies the calculated total duty cycle, referring to the table (Step S708), and then proceeds to Step S706.

For example, the controller **10** determines the duty cycle of the 1100 W halogen lamp heater **187** to be 67% (733 W), referring to the table shown in FIG. 8, and performs duty control.

That is, when the heat amount generated by the 700 W halogen lamp heater **186** has increased to the first threshold value TH91 (total duty cycle of 40.7%), the controller **10** switches the halogen lamp heater to perform duty control thereon from the 700 W halogen lamp heater **186** to the 1100 W halogen lamp heater **187**.

On the other hand, when determining that the currently duty-controlled halogen lamp heater is the 1100 W halogen lamp heater **187** (Step S704; 1100 W), the controller **10** determines whether the total duty cycle has reached a second threshold value TH92 (Step S709).

The second threshold value TH92 is a threshold value to switch from the halogen lamp heater **187** to the halogen

lamp heater **186**, and equivalent to a total duty cycle of 28.5% in the table shown in FIG. 8, for example.

When determining that the total duty cycle has not reached the second threshold value TH92 yet (Step S709; NO), the controller **10** proceeds to Step S705. On the other hand, when determining that the total duty cycle has reached the second threshold value TH92 (Step S709; YES), the controller **10** switches the halogen lamp heater to perform duty control thereon from the 1100 W halogen lamp heater **187** to the 700 W halogen lamp heater **186** and also determines the duty cycle of the halogen lamp heater **186** which satisfies the calculated total duty cycle, referring to the table (Step S710), and then proceeds to Step S706.

For example, the controller **10** determines the duty cycle of the 700 W halogen lamp heater **186** to be 73% (513 W), referring to the table shown in FIG. 8, and performs duty control.

That is, when the heat amount generated by the 1100 W halogen lamp heater **187** has decreased to the second threshold value TH92 (total duty cycle of 28.5%), the controller **10** switches the halogen lamp heater to perform duty control thereon from the 1100 W halogen lamp heater **187** to the 700 W halogen lamp heater **186**.

Thus, the first threshold value TH91 to switch from the 700 W halogen lamp heater **186** to the 1100 W halogen lamp heater **187** and the second threshold value TH92 to switch from the 1100 W halogen lamp heater **187** to the 700 W halogen lamp heater **186** have a relationship of “first threshold value>second threshold value”, namely, have hysteresis.

Hence, even in the range RG91, the total duty cycles in which are covered by either of the halogen lamp heaters being duty-controlled, frequent switching between the two halogen lamp heaters according to the calculated total duty cycle does not occur.

For example, even if the second threshold value TH92 (total duty cycle of 28.5%) is reached, and hence switching from the 1100 W halogen lamp heater **187** to the 700 W halogen lamp heater **186** is performed once, switching from the 700 W halogen lamp heater **186** to the 1100 W halogen lamp heater **187** is not performed until the first threshold value TH91 (total duty cycle of 40.7%) is reached. Hence, frequent switching between the two halogen lamp heaters according to the calculated total duty cycle does not occur.

As described above, when the heat amount generated by the halogen lamp heater **186** has increased to the first threshold value TH91 by the controller **10** controlling the drive voltage to apply, the controller **10** switches the halogen lamp heater to perform duty control thereon from the halogen lamp heater **186** to the halogen lamp heater **187**, and when the heat amount generated by the halogen lamp heater **187** has decreased to the second threshold value TH92 by the controller **10** controlling the drive voltage to apply, the controller **10** switches the halogen lamp heater to perform duty control thereon from the halogen lamp heater **187** to the halogen lamp heater **186**. This can prevent frequent switching between the two halogen lamp heaters and thereby can prevent flicker.

In one or more embodiments, it is assumed that the minimum heat amount and the maximum heat amount required for fixing are 300 W and 1800 W, respectively, but not limited thereto as a matter of course. These values depend on the size, capacity and so forth of an image forming apparatus.

Further, in one or more embodiments, the predetermined duty cycle to generate the heat amount required to prevent chemical attack (breaking of filaments) is 40%, but not limited thereto as a matter of course. The predetermined

11

duty cycle is different for each halogen lamp heater and changes depending on, for example, the concentration of the halogen gas with which the halogen lamp heater is filled.

Further, in one or more embodiments, the fixing roller 183 and the pressure roller 184 of the image fixing unit 18 form the fixing nip to sandwich and convey paper P. Alternatively, the image fixing unit 18 may include a heating roller as a heating member and a fixing belt stretched around the heating roller and the fixing roller 183, and the fixing roller 183 and the pressure roller 184 may form the fixing nip to sandwich and convey paper P via the fixing belt. 10

Further, in one or more embodiments, the image forming apparatus 1 includes the image forming sections for the respective colors of Y (yellow), M (magenta), C (cyan) and K (black), and forms multi-color images on paper P. The image forming apparatus 1 is not limited thereto and may be an image forming apparatus which forms monochrome images. 15

Further, in one or more embodiments, the fixing roller and the pressure roller are separately described, but may be regarded as a pair of fixing members. 20

Further, in one or more embodiments, paper is used as the recording medium. The recording medium is not limited to paper and may be any as long as it is in the shape of a sheet and can have toner images formed and fixed there. Examples thereof include nonwoven fabric, plastic films and leather. 25

Although the disclosure has been described with respect to only a limited number of embodiments, those skilled in the art, having benefit of this disclosure, will appreciate that various other embodiments may be devised without departing from the scope of the present invention. Accordingly, the scope of the invention should be limited only by the attached claims 30

What is claimed is:

1. An image forming apparatus comprising:
a first halogen lamp heater and a second halogen lamp heater having a same light distribution as the first halogen lamp heater, wherein the first and second halogen lamp heaters heat a roller of an image fixing unit, and the second halogen lamp heater generates less heat than the first halogen lamp heater; 35
an AC power supply;
a temperature sensor that detects a temperature of the roller; and
a controller that determines a combined heat amount of the first and second halogen lamp heaters based on an output of the temperature sensor, and applies a drive voltage of a half-wave of an AC waveform of the AC power supply to one of the first and second halogen lamp heaters, wherein 40

45

12

the half-wave is selected based on an application pattern having a duty cycle greater than or equal to a predetermined value,

the second halogen lamp heater generates no more than a minimum heat amount required to perform fixing when turned on with the application pattern having the duty cycle equal to the predetermined value,

when a heat amount generated by the second halogen lamp heater has increased to a first threshold value, the controller turns off the second halogen lamp heater to which the drive voltage is applied, and turns on the first halogen lamp heater, and

when a heat amount generated by the first halogen lamp heater has decreased to a second threshold value smaller than the first threshold value, the controller turns off the first halogen lamp heater, to which the drive voltage is applied, and turns on the second halogen lamp heater. 10

2. The image forming apparatus according to claim 1, wherein

the controller refers to a table containing information about the combined heat amount of the first and second halogen lamp heaters and the duty cycle of the predetermined value, and

the controller calculates a required heat amount based on the output of the temperature sensor, and selects the combined heat amount of the first and second halogen lamp heaters and the duty cycle that satisfy the required heat amount. 15

3. The image forming apparatus according to claim 1, wherein

the first threshold value is a maximum heat amount generated by the second halogen lamp heater, and the second threshold value is a heat amount generated by the first halogen lamp heater turned on with the application pattern having the duty cycle of the predetermined value. 20

4. The image forming apparatus according to claim 1, wherein the controller fully turns on the first halogen lamp heater and applies the drive voltage to the second halogen lamp heater when a heat amount required for fixing is more than a maximum heat amount generated by the first halogen lamp heater. 25

5. The image forming apparatus according to claim 1, wherein a heat amount generated by either of the first and second halogen lamp heaters turned on with the application pattern having the duty cycle of the predetermined value is a heat amount required to prevent breaking of a filament of either of the first and second halogen lamp heaters. 30
